UNITED STATES PATENT OFFICE.

FRED L. MACKENZIE, OF BEVERLY, AND GEORGE GODDU, OF WINCHESTER, MASSACHUSETTS, ASSIGNEES TO UNITED SHOE MACHINERY CORPORATION, OF PATERSON, NEW JERSEY, A CORPORATION OF NEW JERSEY.

FASTENING-INSERTING MACHINE.

Application filed April 19, 1919. Serial No. 291,246.

This invention relates to fastening inserting machines and is disclosed herein as embodied in a machine of a type in which perforating means are provided for forming 5 perforations in the work preliminary to the insertion of the fastenings.

In certain classes of shoes, and especially in shoes for women, it has become very common to provide wooden heels which are ordinarily finished by covering with cloth, leather, or other suitable material. In all wooden heels, however finished, it is considered desirable to provide a toplift, for example of leather, which is commonly secured in 10 position by the use of a plurality of fine tacks or nails and a single relatively large nail driven through the top lift and into the wooden heel substantially at the center of the tread surface. Heretofore these fastenings 15 including the large fastening have been driven by means of a well-known type of fastening inserting mechanism, special provision being made for insuring the proper setting of the large size fastening. As a result, it occasionally happens that the wooden 20 heel is split or otherwise damaged by the driving of the large fastening and even where this does not occur the fastening is frequently set at such an angle that an edge 25 of the head of the fastening projects above the surface of the top lift and interferes with the subsequent finishing operations and otherwise mars the appearance of the finished article.

Accordingly, it is an object of this invention to provide fastening inserting mechanism operative to insure the perfect setting of the relatively large fastening which is depended upon to attach the toplift securely 30 to the wooden heel. To effect this desired result the illustrated machine is provided with means for making suitable perforations in the proper locations in toplifts and in the wooden portions of heels so that fastenings 35 may be driven perfectly with their head surfaces flush with the surface of the toplifts.

A feature of importance consists in the provision of work positioning means for the inserting mechanism and for the drill so 40 constructed and arranged that the opening made by the drill is presented correctly for the insertion of the fastening. Furthermore, the work positioning means is so designed as to gage from the plane surface of

the toplift, thus insuring that the fastening will be driven in all cases in a direction perpendicular to the tread surface and, therefore, that the head of the fastening will be perfectly set with its exposed surface in the same plane with the tread surface of the toplift.

Other objects and features of the invention will be set forth in the accompanying specification and will be pointed out in the claims.

In the drawings,

Fig. 1 is a side view of an illustrative machine;

Fig. 2 is a plan view of a detached presser plate and gage member;

Fig. 3 is a front view of the machine shown in Fig. 1; and

Fig. 4 is a view of the combined presser foot and gage member as viewed from the front of the machine.

In the illustrative machine, the fastening inserting mechanism comprises a driver 6 carried by a driver bar 8 arranged to be urged downwardly by the spring pressed member 10 and to be lifted after each operative stroke by a cam 12 on the front of the main shaft. Fastenings are provided for the fastening inserting operations by means of a hopper 14 connected by a raceway 16 with a stationary nozzle 18 screwed into the lower front portion of the frame 19 and to which fastenings are delivered one by one through the operation of fastening separator mechanism not shown. The work positioning means for the fastening inserting 45 mechanism comprises preferably a presser foot or plate 20 arranged to slide vertically on the stationary nozzle and being further guided by a slidable connection with a pin 22 connected to and extending downwardly from the frame of the machine and through an opening 24 in the rear end of the presser plate. Plate 20 is supported by a pin and slot connection with a lever hereinafter described. Mounted adjustably on the presser plate 20 is a gage member 26, preferably in the form of a member having a V-shaped notch with the wings of the V facing forwardly and designed to engage on opposite sides of the heel as the latter is presented to the presser plate and thus to position the heel against rearward or sidewise movement.

Since the fastening should be driven vertically

cally into the heel the under surface of the presser plate 20 is arranged in a plane at a right angle to the direction of fastening insertion and the gage member 26 is adjusted 5 on the presser plate so as to position the heel with substantially the center point of the tread surface in the line of drive. A similar work positioning means is preferably provided for the perforating mechanism to be 10 described later so that the opening or perforation made by the perforating means will be provided at the location where it is desired later to drive the fastening. Preferably and as shown, the fastening inserting mechanism is controlled from the presser plate so that as the latter is moved upwardly with the work the fastening inserting mechanism is caused to operate to insert a fastening. The means for controlling the 15 starting and stopping of the machine is of the type shown in the patent to Woodward No. 389,275, September 11, 1888, and comprises preferably a lever 28 movably attached by a pin and slot connection with the 20 presser plate 20 by a pin 30 extending laterally from a projection 31 on the plate 20 and through a slot in the frame 19 and through a slot in the lever so that as the presser plate is moved upwardly on presentation of the 25 work thereto the lever 28 is caused to move about its pivot point 33 to cause the tripping of the clutch. Power is supplied to the main shaft of the machine through pulley 32 which is urged in a direction to engage 30 a cone member (not shown) on said shaft by means of a pivoted member 34 which is pulled in the proper direction by means of a spring 36 attached to the upper end of said member 34 and to a stud 38 on 35 the frame of the machine. The member 34 and the connected pulley 32 are normally held in clutch releasing position by means of a latch 40 adjustably pivoted at 42 and carrying a catch plate 44 arranged to engage 40 a second catch plate 46 on the member 34. Latch 40 is normally held in operative position by a spring 48 as clearly shown in Fig. 45 1 of the drawings. In order to release latch 40 and thus permit clutch engaging movement of the pulley 32 there is provided a link member 50 pivoted to the rear end of the lever 28 and provided at its upper end with a hook 52 designed to engage a pin (not shown) on the inner side of latch 40, a 50 spring 54 being provided for returning the hook member 52 to its pin engaging position after it has been depressed by the operation of lever 28. It will be clear that upon pressing the work against the presser plate 20 to cause upward movement thereof lever 28 will be operated and thus produce downward movement of the hook member 50, thus causing the release of the latch member 40 55 60 65 66 67 68 69 70 71 72 73 74 75 76 77 78 79 80 81 82 83 84 85 86 87 88 89 90 91 92 93 94 95 96 97 98 99 100 101 102 103 104 105 106 107 108 109 110 111 112 113 114 115 116 117 118 119 120 121 122 123 124 125 126 127 128 129 130

34, together with the pulley 32, moves to the right under the action of spring 36 to cause the engagement of the clutch with the consequent operation of the fastening inserting mechanism through the aforementioned main shaft. As will be seen from an inspection of Fig. 1, the latch 40 is pivotally mounted on a lever 56 pivoted at its lower end at the point 33 and carrying at its upper end a roll arranged in a cam slot 58 in the cam 60 on the said main shaft, the arrangement being such that the latch 40 is carried to the left toward the termination of one revolution of said shaft to cause the engagement of catch plate 44 with the catch plate 46 and the consequent movement of the pulley 32 to clutch releasing position, the spring 48 assisting in this operation by returning the operative end of the latch 40 to its normal uppermost position. At the same time that the pulley 32 and the member 34 move toward the left in Fig. 1, as described, a brake mechanism indicated generally by reference character 62, and disclosed more fully in said patent to Woodward, is caused to operate to assist in the stopping of the main shaft at the termination of one revolution.

A work support is preferably provided for moving the work into contact with presser plate 20 and to cause the operation of the inserting mechanism, said support comprising preferably a post 64 vertically slidable in guide members, one of which is shown at 66 and provided with a treadle mechanism (not shown) for causing movement of the post upwardly upon actuation of the treadle. At the upper end of the post 64 there is provided a work engaging member 68 designed to conform to and suitably engage the concaved heel seat portion of the heel. As shown, this member is preferably provided with a curved and roughened surface 69 for engaging the aforementioned portion of the heel and holding the same properly while it is being pressed against the presser plate.

Mounted on a bracket 70 extending from the frame or standard 72 of the machine is a perforating mechanism which, in the illustrated embodiment of the machine, is shown to comprise a drill mechanism 74 having as its principal element a drill 76 arranged to be continuously driven from a pulley 78 connected by a belt 80 with a large pulley 82 on a counter shaft 84 mounted in the bracket 70 and arranged in turn to be driven from a pulley 86 driven by means of a belt 88 which passes around a pulley 90 fixedly attached to the power pulley 32. Normally, the drill will be running continuously during the operation of the machine. Should it be desired, however, to use the inserting mechanism for any length of time without making use of the drill mechanism the ro-

tary movements of the latter may be terminated by shifting the hand lever 92 to the left in Fig. 1 of the drawings, thus permitting the spring 94 to move the clutch carrying sleeve 96 to the left, so that the friction clutch indicated at 98 is moved into clutch releasing position, pulley 86 under these conditions running idly and not effecting movement of the pulley 82. It will be noted 5 that no work support, with respect to which the work would have to be positioned, is provided and that the drill mechanism is mounted stationarily in a substantially horizontal plane so that the operative can readily 10 present the work thereto by shoving the heel upon the drill as he stands in front of the machine. This operation requires little effort since the heel is not being moved upwardly but in a direction which requires the 15 minimum of effort since a slight movement forward of the hand or the hand and body of the operative is sufficient to effect the proper engagement of the work with the revolving drill.

15 In order to facilitate the presentation of the work to the drill there is provided a work positioning means which preferably takes the same form as that described in connection with the inserting mechanism. 20 As illustrated, it comprises a plate 100 mounted on a block 102 carried by a rod 104 mounted for endwise movement in the bracket 70 and normally held yieldingly in 25 forward position by a spring 106 located in sockets in alignment with each other in the bracket and in the block 102 as clearly disclosed in Fig. 1. When the work is pressed against the plate 100 the latter moves toward the drill which thus perforates the 30 work, the movement of the plate to permit the drilling operation being limited by the engagement of an adjustable screw threaded member 108 with an abutment 110 upon the bracket member 70. The construction of the 35 drill 76 with an enlarged portion at a predetermined distance from the free end of the drill and the arrangement of the work positioning means with respect to the drill are such that an opening of proper depth is 40 made in the toplift and heel 111 and there is provided also an enlargement of the opening at the surface of the toplift so that the head of the inserted fastening will be countersunk with its surface flush with the tread 45 surface of the heel. In order to locate the heel so as to perforate the same at substantially the center point of the tread surface thereof there is provided a gage 112 which is preferably of the same type as that 50 described in connection with the work positioning means for the inserting mechanism. As illustrated, this gage is formed with a V-shaped notch and is mounted adjustably 55 as indicated at 114 upon the block 102 which 60 carries the presser plate 100. Since the gage 65 is adjustably mounted it may be readily located so that heels of various sizes may be properly positioned to have an opening drilled therein substantially centrally of the tread surface. It will be understood that 70 the work positioning means of the drill mechanism and that used in connection with the inserting mechanism will be so adjusted that the opening formed by the drill will be exactly positioned beneath the inserting 75 mechanism for the insertion of a fastening in said opening. It should be noted, moreover, that the work is positioned for both the drilling and the fastening inserting operations by contact with the plane or tread surface of the heel, thus insuring that the fastenings will be driven perpendicularly into the work and removing the possibility of having a fastening so misplaced as to present an edge projecting above or beyond the 80 tread surface where, as before stated, it would interfere with the finishing operations and be otherwise objectionable from the standpoint of the appearance of the finished work.

80 In operating with the machine which has just been described, the operative first engages a heel, to which a top lift has been preliminarily attached in any suitable way, with the presser plate 100 in such a way 85 that the tread surface of the heel is flatly engaged with the plate 100 and with side portions of the heel in contact with the arms of the gage 112. Slight pressure in a substantially horizontal direction causes the 90 work positioning means to yield and permits the work to move upon the continuously rotating drill so that an appropriate hole is drilled in the heel. After this has been accomplished the heel is transferred to a position beneath the inserting mechanism and the tread surface is engaged with the pressure plate 20 and the sides of the heel with the corresponding gage 26 so that the heel is positioned in the positioning means to 95 correspond with its previous position while being subjected to the drilling operation and hence a fastening will be driven exactly into the perforation provided for that purpose. After the heel has been engaged with the 100 positioning means below the inserting mechanism, depression of the treadle causes upward movement of the work support 68 first to engage the work and then to carry it upwardly to cause the tripping of the clutch 105 on the main shaft and the proper operation of the inserting mechanism.

110 Having fully described our invention what we claim as new and desire to secure by Letters Patent of the United States is:

115 1. In a machine of the class described, means for operating on work, and means for presenting the work to said means comprising a member designed to locate the work and limit the movement thereof in either of 120

two directions transverse to each other and arranged to be movable in the direction of operation of the work operating means to control the operation of said work operating means.

2. In a fastening inserting machine, fastening inserting mechanism, means for starting and stopping the machine, and means for positioning the work against movement in either of two directions transverse to each other and arranged to be movable in the direction of fastening insertion to control said starting and stopping means.

3. In a fastening inserting machine, mechanism for inserting fastenings having a nozzle for guiding the fastenings during insertion into work, and means for positioning the work relatively to said mechanism comprising a member movable upwardly on the nozzle as the work is presented thereto and designed to engage surfaces on the work angularly related to each other to control accurately the presentation of the work to said inserting mechanism.

4. In a fastening inserting machine, fastening inserting mechanism, and means for positioning the work relatively thereto comprising a presser foot relatively movable with respect to the inserting mechanism to control the operation thereof and a gage secured to said presser foot and designed to present the work in predetermined relation to said inserting mechanism.

5. In a fastening inserting machine, fastening inserting mechanism having a nozzle, and means for positioning the work relatively thereto comprising a member movable on the nozzle of the inserting mechanism and a gage on said member operative to center the work for determining the point of insertion of the fastening.

6. In a machine for fastening top lifts to heels, mechanism for inserting fastenings singly through the top lift and into the heel, and means for positioning the top lift and heel relatively to said mechanism comprising a member movable with respect to said mechanism and designed to engage the tread surface of the top lift to determine the angle at which the fastening is driven and notched to contact with the edge of the top lift to insure the driving of the fastening at a predetermined point in the lift.

7. A machine for operating upon shoe parts having, in combination, an operating tool, a support adjacent to the tool and a gage member shaped for engagement with the work to position the work against movement in transverse directions in the same plane and yieldingly mounted upon the support, the gage members and the support being provided with interengaging means for preventing movement of the gage member except in a path toward and from the support.

8. A machine for operating upon shoe parts having, in combination, an operating tool, a support adjacent to the tool, a gage member shaped for engagement with the work to position the work against movement in transverse directions in the same plane movably mounted upon the support and tending to move away from the tool, the gage member and the support being provided with interengaging means for preventing relative movement of the gage member and the tool except in a path toward and from the tool.

In testimony whereof we have signed our names to this specification.

FRED L. MACKENZIE.
GEORGE GODDU.

- two directions transverse to each other and arranged to be movable in the direction of operation of the work operating means to control the operation of said work operating means.
2. In a fastening inserting machine, fastening inserting mechanism, means for starting and stopping the machine, and means for positioning the work against movement in either of two directions transverse to each other and arranged to be movable in the direction of fastening insertion to control said starting and stopping means.
3. In a fastening inserting machine, mechanism for inserting fastenings having a nozzle for guiding the fastenings during insertion into work, and means for positioning the work relatively to said mechanism comprising a member movable upwardly on the nozzle as the work is presented thereto and designed to engage surfaces on the work angularly related to each other to control accurately the presentation of the work to said inserting mechanism.
4. In a fastening inserting machine, fastening inserting mechanism, and means for positioning the work relatively thereto comprising a presser foot relatively movable with respect to the inserting mechanism to control the operation thereof and a gage secured to said presser foot and designed to present the work in predetermined relation to said inserting mechanism.
5. In a fastening inserting machine, fastening inserting mechanism having a nozzle, and means for positioning the work relatively thereto comprising a member movable on the nozzle of the inserting mechanism and a gage on said member operative to center the work for determining the point of insertion of the fastening.
6. In a machine for fastening top lifts to heels, mechanism for inserting fastenings singly through the top lift and into the heel, and means for positioning the top lift and heel relatively to said mechanism comprising a member movable with respect to said mechanism and designed to engage the tread surface of the top lift to determine the angle at which the fastening is driven and notched to contact with the edge of the top lift to insure the driving of the fastening at a predetermined point in the lift.
7. A machine for operating upon shoe parts having, in combination, an operating tool, a support adjacent to the tool and a gage member shaped for engagement with the work to position the work against movement in transverse directions in the same plane and yieldingly mounted upon the support, the gage members and the support being provided with interengaging means for preventing movement of the gage member except in a path toward and from the support.
8. A machine for operating upon shoe parts having, in combination, an operating tool, a support adjacent to the tool, a gage member shaped for engagement with the work to position the work against movement in transverse directions in the same plane movably mounted upon the support and tending to move away from the tool, the gage member and the support being provided with interengaging means for preventing relative movement of the gage member and the tool except in a path toward and from the tool.

In testimony whereof we have signed our names to this specification.
